UNITED STATES PATENT OFFICE.

EDWIN F. GUTH, OF ST. LOUIS, MISSOURI.

LIGHTING-FIXTURE.

1,146,935.

Specification of Letters Patent. Patented July 20, 1915.

Application filed November 14, 1914. Serial No. 872,060.

To all whom it may concern:

Be it known that I, EDWIN F. GUTH, a citizen of the United States of America, residing at the city of St. Louis, State of Missouri, have invented a certain new and useful Lighting-Fixture, of which the following is such a full, clear, and exact description as will enable any one skilled in the art to which it appertains to make and use 10 the same, reference being had to the accompanying drawings, forming part of this specification.

My invention relates to a light controlling device or fixture designed to operate 15 on a principle similar to that of the fixture described in my United States Patent No. 1,076,418, its object being to approximate the lighting effects of what is known as "indirect lighting" and also to utilize the 20 light produced by the lamp more efficiently than is possible in an indirect lighting system, while, at the same time, eliminating direct rays of light from the working plane or space where light is desired.

25 One object of the invention is to provide a device for the general purpose described which shall be very simple in construction and low in cost.

Another object is to provide means where- 30 by the heat produced by the lamp may be sufficiently dissipated and the temperature within the fixture kept within proper limits, means for dissipating heat being particu- 35 larly necessary in connection with electric lights operating in nitrogen, argon, or other gases.

A still further object is to so arrange the 40 ventilating means as to avoid accumulation of dust within the fixture.

45 In the accompanying drawings, which illustrate one embodiment of my invention, Figure 1 is a side view, partly in section and partly in elevation, and Fig. 2 is a bottom plan view.

50 1 designates a translucent glass bowl sur- 55 rounding a source of light 2 and provided with an integral top 3. An opening 4 in this top is of sufficient size to permit the insertion of the light source 2 and is closed after the insertion of the light by means of a suitable cover plate or member 5 which may also serve as a support for the bowl and for the light source. The top 3 is so constructed as to afford a good reflecting surface for the light passing upward from the source, this reflecting sur-

face being preferably flat. I prefer to so construct this top of glass or other suitable material that although the greater part of the light will be reflected downwardly 60 thereby, a small portion of it may pass through the top and toward the upper part of the room to be lighted. To secure the last named result, the top may be constructed of what is known as opal glass. 65

The upper portion of the bowl is preferably flared as shown and spaced ventilating openings 6 are made in this flared portion and a ventilating opening 7 is provided in the lower portion of the bowl. With this 70 arrangement of openings, the heat of the lamp causes circulation of air through the fixture and the position of the openings 6 is such that dust or other foreign material cannot fall into them. 75

It will be noted that with the construction described, practically all the rays of light passing upwardly from the source will be directed downwardly and distributed and that the light passing downwardly will be 80 diffused by the translucent bowl with the result that the entire working plane beneath the fixture will be evenly lighted with a soft pleasing light, and, further, that practically all of the light will be directed toward this working plane and thus most efficient use made of the light produced. The small amount of light passing through the upper portion of the bowl in the preferred 85 form of construction is sufficient to prevent formation of shadows on the ceiling of the room. 90

Since it is possible to make the bowl and upper reflecting surface of glass in one piece, the cost of construction is relatively 95 low.

Having fully described my invention, what I claim as new and desire to secure by Letters-Patent of the United States is:

1. A light controlling device comprising 100 a translucent glass bowl having an integral glass top provided with a substantially flat reflecting surface, the upper portion of the bowl being flared and provided with spaced ventilating openings in said flared portion. 105

2. A light controlling device comprising 110 a translucent glass bowl having an integral glass top provided with a reflecting surface, the upper portion of the bowl being flared and provided with spaced ventilating openings in the flared portion and a ventilating opening in the bottom.

3. A light controlling device comprising a translucent glass bowl having a glass top integral with the bowl and provided with an opening for the insertion of a source of light, and a cover for said opening, said bowl being provided with spaced openings near its top and an opening in the bottom.
4. A lighting fixture comprising a light diffusing bowl having an integral glass top provided with a central opening, the upper portion of said bowl being flared and provided with spaced ventilating openings in said upper portion, a source of light within the bowl, means for supporting the bowl from the top, said means also forming a support for the light and a cover for the opening in the top of the bowl.

5. A light controlling device comprising a translucent glass bowl having an integral opal glass top provided with a substantially

flat reflecting surface and having a central opening for the insertion of a source of light, bowl supporting means attached to said top, the upper portion of the bowl being flared and provided with spaced ventilating openings in said flared portion and an opening in the bottom.

6. A light controlling device comprising a translucent bowl having a top provided with a reflecting surface, the upper part of the bowl being flared and provided with ventilating openings in the flared portion.

In testimony whereof, I have hereunto set my hand and affixed my seal in the presence of the two subscribing witnesses.

EDWIN F. GUTH. [L. S.]
